UNITED STATES PATENT OFFICE.

PETER JOHN FRITGEN, OF RANDOLPH, NEBRASKA.

HINGE.

Application filed October 27, 1921. Serial No. 510,721.

To all whom it may concern:

Be it known that I, PETER J. FRITGEN, a citizen of the United States, residing at Randolph, in the county of Cedar and State 5 of Nebraska, have invented certain new and useful Improvements in Hinges, of which the following is a specification, reference being had therein to the accompanying drawings.

10 This invention relates to hinges and has for an object to provide a hinge especially adapted for use in conjunction and association with a gate, although obviously not limited to a gate structure.

15 A further object of the invention is to provide a hinge which, when associated with a gate, or the like, permits the free opening of the gate in either direction, raising such gate against gravity, whereby the gate closes 20 of its own accord when released.

25 A further object of the invention is to provide a hinge embodying adjacently disposed pipes, tubes of the like into the ends of which or about which hinge members are associated to carry out the function and 30 object of the invention just mentioned.

With these and other objects in view the device comprises certain novel parts, elements, units, members, combinations, mechanical movements and functions, as disclosed in the drawings, together with mechanical equivalents thereof as will be hereinafter more fully described and claimed.

In the drawings:

35 Figure 1 is a view of the device in side elevation;

Figure 2 is a view of the device with the gate open, seen in side elevation;

40 Figure 3 is a transverse sectional view taken on line 3—3 of Figure 1;

Figure 4 is a fragmentary detail perspective view of the hinge and gate removed from the supporting post;

45 Figure 5 is a view in side elevation of a different type of hinge mounting;

Figure 6 is a view of the type of hinge mounting shown at Figure 5 with the gate shown in open position;

50 Figure 7 is a transverse sectional view through the supporting structure of the type shown at and taken on line 7—7 of Figure 5, and

55 Figure 8 is a detail perspective view of the type of hinge employed in the embodiment shown at Figures 5 and 6.

Like characters of reference indicate cor-

responding parts throughout the several views.

As shown in the drawings, a gate 10 is indicated as associated with the hinge, but the gate itself is shown only as a means of illustrating the action and mounting of the hinge and has no specific bearing thereon. Also the post 11 carrying the latch 12 has no specific relation to the hinge to which this invention is directed but some such post and latch are necessary to the complete functioning of the hinge.

A post 13 of any usual and ordinary type is employed, although preferably circular in cross section and also preferably, though not necessarily, tubular, is employed and set into or supported relative to the ground in any usual and ordinary manner. To this post a tubular member 14 is attached in any 75 one of several different manners, one of which is by the interposition of a third tubular member 15, as shown at Figures 1 and 3, employing bridge members 16, or by interposing the bridge members as 16' 80 directly between the post 13 and the tubular member 14, as shown at Figures 5 and 7.

In either instance the hinge comprises a hook 17 which hooks into the top of the tubular member 14 and is ordinarily secured 85 to the gate or like structure in any approved manner, as by forming integral with the bar 18 extending downwardly along the edge of the gate or other panel to which it is attached. The formation of the hook as 90 shown at 17, especially at Figures 4 and 8, is such as to permit a lateral or swinging movement of the hook relative to the top end of the tubular member 14. In the structure as shown at Figures 1 and 2 a second 95 hook 19 is upwardly turned from the bar 18 and inserted in the lower end of the tube 15 which, as will be noted, is spaced from the tubular member 14, a long shank 20 being interposed between the hook and the bar 18 for that purpose. In the type shown at Figures 5 and 6 the extended arm 20' carries a ring 21 embracing the post 13, the spacing of the tubular member 14 and the post 13 being substantially the same as the 100 spacing of the tubular member 14 and the pipe 15. In either event the structure is secured rigidly together in any approved manner, as by the employment of bolts 22 which extend through the bridge members 110 16 or 16'.

It will be noted, of course, that the gate

member is free to swing about the hook 17 at the top as a supporting pivot and the hook 19 or the ring 20 at the bottom and when swung to lateral position will be inclined as shown at Figures 2 and 6 against the force of gravity, whereby the release of the gate from such position will cause it to swing to normal and to be engaged and retained by the automatic catch, one type of 10 which is illustrated at 12.

It is believed that the operation of the device will be clearly understood from the foregoing description.

What I claim is:

- 15 1. The combination with a swinging panel of a post structure embodying spaced vertical sections, a hinge member carried by the panel having at its upper end a trunnion inserted into and pivoting about the proximate member and at its bottom means forming a pivot about the remote member.
- 20 2. The combination with a swinging panel of a post structure embodying spaced vertical sections lying substantially in the same

normal plane of the panel, a hinge member 25 carried by the panel having at its upper end a trunnion inserted into and pivoting about the proximate member and at its bottom an arm extending under and beyond the proximate member and provided with means 30 forming a pivot about the remote member.

3. The combination with a swinging panel of a post comprising members spaced in a plane coinciding with the normal plane of the panel, a hook carried at the upper end 35 of the panel engaging in the top of the member nearest the panel, and a pivoting member carried by the panel extending under the said post member and forming pivotal engagement with the other post member at a point more remote from the gate than the pivoting at the top.

In testimony whereof I hereunto affix my signature in presence of two witnesses.

PETER JOHN FRITGEN.
